UNITED STATES PATENT OFFICE.

ISIDORE CLAIR, OF BROOKLYN, NEW YORK.

NAIL-BUFFER.

1,369,619.

Specification of Letters Patent. Patented Feb. 22, 1921.

Application filed August 3, 1920. Serial No. 400,961.

To all whom it may concern:

Be it known that I, ISIDORE CLAIR, a citizen of the United States, and a resident of the city of New York, borough of Brooklyn, 5 in the county of Kings and State of New York, have invented a new and useful Nail-Buffer, of which the following is a full, clear, and exact description.

This invention relates to nail buffers and 10 has for an object to provide an improved construction wherein the buffing part may be readily removed and a new one substituted.

Another object of the invention is to provide a buffer in which the buffing leather or 15 material may be reversed.

A still further object of the invention is to provide a buffer with a removable buffing surface and a removable padding means whereby the tension of the buffing surface 20 may be varied.

In the accompanying drawing:

Figure 1 is a perspective view of a buffer disclosing an embodiment of the invention.

Fig. 2 is a longitudinal vertical section 25 through Fig. 1 approximately on line 2—2.

Fig. 3 is a perspective view of one of the tension pads removed.

Fig. 4 is a perspective view of a buffing member partially reversed.

Fig. 5 is an enlarged fragmentary sectional view showing a slightly modified form of retaining means for the buffing member shown in Fig. 4.

Referring to the accompanying drawing 35 by numerals, 1 indicates the body of the buffer which is provided with a handle 2 of any desired construction, the handle and body being formed of any suitable material and preferably provided with an overhang 3 and a notched portion 4. The rim 5 of the buffing member 6 fits beneath the overhang 3 so that the leather or other buffing material of the buffing member 6 may fit into the recess or notch 4. The buffing member 40 6 is provided with a buffing body 7 of chamois or other suitable material which is preferably provided with a smooth face on one side and a comparatively rough face on the opposite side. The buffing material

45 7 is formed to fit properly the body 1 and is arranged with its upper edge in the rim 5 which holds the same permanently in place and under the desired tension. The rim 5 is composed of a band 8 of suitable material, 50 as for instance metal, and around this metal band is looped the edge of the member 6 as

shown in Fig. 5 after which a second band of metal 9 is looped or bent around the looped edge of the material 7. This effectively clamps the edge of the material 7 in 60 place and presents a complete stiff ring. This ring is provided with a pair of apertures 10 and 11 at each end through which the pins 12 and 13 extend, said pins extending into the body 1. If desired similar pins 65 could be arranged on the sides though ordinarily this is not necessary. Preferably pin 12 is provided with a large head so that it will remain in proper place and hold the parts assembled while preferably the pin 13 70 is provided with a looped portion or eye 14 which carries a ring 15 though if desired both pins could be formed alike.

In addition a modified arrangement could be provided for holding the rim 5 and associate parts assembled with body 1. This modified arrangement is shown in Fig. 5 and consists of a spring 16 held in place by a screw pin or other securing means 17. The spring 16 is inclined at 18 and is provided with an interlocking extension 19 adapted to snap into one of the apertures 10 or 11 according to which edge of the rim 5 is uppermost. When it is desired to remove the rim 5 from the structure shown in 80 Fig. 5 a small pincer is inserted in aperture 11 and the spring 16 pressed back until it is disengaged whereupon the rim 5 may freely move downwardly. To remove the member 5 including rim 5 when using the pins 12 85 and 13 it is necessary to first pull out these pins and then pull downwardly on the rim. This arrangement of removable buffing member permits the material of the buffing member to be reversed as indicated in Fig. 4 90 and in order to secure either a rough or smooth surface if the material is so formed or to secure the use of a second surface. When the material 7 is reversed the aperture 10 in Fig. 5 will be engaged by the extension 19. The pins 12 and 13, of course, will extend through the aperture 10 when rim 5 95 is reversed.

In order to have a comparatively solid body and yet provide a more or less yielding or resilient effect one or more cushioning members of felt or other suitable material 20 is arranged between the body 1 and the material 7 of the buffing member 6. If desired several of the felt pads could be 100 provided in order to produce whatever tension desired on the material 7. After a 110

buffer has been used for some time the material 7 may stretch somewhat and consequently becomes loose to a certain extent. If this should occur an additional felt pad 5 20 could be used and the tautness of the material restored.

What I claim is:

1. A nail buffer comprising a body, a removable buffering member mounted on the 10 body formed with apertures adjacent each end, and a spring connected to said body adjacent each end, said springs being formed with projections adapted to snap into said apertures for locking the buffering member in 15 place on the body.

2. A nail buffer comprising a buffer body, a reversible buffering member having a section of buffering material adapted to fit over part of the body, and a retaining ring rigidly connected with the edge of the buffering material provided with two openings at each end, and pins interlocking with said body and extending through one set of openings in said ring when one side of said buffering material is facing outwardly and extending 25 through the other set of openings in said ring when the other side of said buffering material is facing outwardly for locking the buffering member on said body.

ISIDORE CLAIR.
